E. B. LEAR

MOUNTING FOR ROCK DRILLS

Filed June 25, 1927

INVENTOR.
Earl B. Lear
BY *Herb G. Leder*
HIS ATTORNEY

UNITED STATES PATENT OFFICE.

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY.

MOUNTING FOR ROCK DRILLS.

Application filed June 25, 1927. Serial No. 201,426.

This invention relates to rock drills, but more particularly to a carriage adapted to be attached to a rock drill of the hand held type.

5 It is an object of the invention to render a hand supported rock drill, such as a sinker, capable of being used as a drifter.

Other objects will appear hereinafter, and to all of these ends the invention consists of the combination of elements and features of construction substantially as herein-after described and claimed and illustrated in the accompanying drawings, in which

15 Figure 1 is a longitudinal elevation, partly in section, of a rock drill having the invention applied thereto,

Figure 2 is a transverse view taken through Figure 1 on the line 2—2 looking in the direction indicated by the arrows, and

20 Figure 3 is a perspective view of the carriage.

Referring to the drawings, A designates a rock drill, only the casing parts of which are shown. These parts in the present instance comprise a cylinder B at the front end of which is disposed a front head C secured in operative position with respect to the cylinder B by side bolts D. At the rearward end of the cylinder B are located the usual 25 rotation devices only the casing parts E of which are shown.

The parts so far described are intended to illustrate a rock drill of the hand held type, such as a sinker or other hand held tools 30 which are ordinarily provided with handles whereby the drill may be guided and supported by the operator.

In accordance with the present invention, the usual back head and associated handle ordinarily carried by the drill has been replaced by a back head F resembling in most respects the type of back heads usually provided on rock drills of the drifter type. The back head F is also held in operative 45 position by the side bolts D and may be equipped with the usual water cleansing devices of which only the water tube G is indicated.

Means are provided to render the drill A capable of use as a drifter, that is, for drilling inclined and horizontal holes. These means comprise a carriage H having a support or bearing J on its front end in which is formed a recess K shaped generally to conform to the surface of the front portion of

the drill, such as the front end of the cylinder B. In the present instance bolts L are disposed in the outer extremities of the bearing J and said bolts L extend with their upper ends through a clamping plate O which, 60 like the bearing J, also conforms to the surface of the casing parts of that portion of the drill wherewith it is adapted to cooperate.

The bolts L are of a suitable length to receive nuts P on the threaded ends thereof whereby the clamping plate O may be securely pressed against the body of the drill A. The bolts L in this instance are so spaced with respect to the drill that they 70 lie between the side bolts D and, as in the present instance, a front cylinder washer Q interposed between the front head C and the cylinder B. To accommodate the bolts L grooves R are formed in the sides of the front cylinder washer Q and these grooves R thus also tend to prevent relative rotation between the carriage H and the rock drill A at the forward end of the carriage.

On opposite sides of the body portion S 80 of the carriage H are formed ribs or guides T which are adapted to slide in guideways U of a rock drill shell V. The shell V may be of any well known type in which means such as a cone W are provided for cooperation with the clamping means carried by a column or other suitable supporting means.

In common with shells of the type disclosed, the shell V is equipped with a usual feed screw X for moving a rock drill or, 90 as in the present instance, the rock drill and the carriage longitudinally of the shell in order to feed the rock drill to the work and retract it therefrom. The feed screw X in this instance is threaded through a 95 feed nut Y which extends through apertures Z and b in the rearward end of the carriage H and a lug c on the back head F respectively.

In addition to the function described, the 100 feed nut Y also acts as a means for clamping the rearward end of the carriage H securely to the lug c. For this purpose the feed nut Y is provided at its front end with a head d to bear against the carriage H 105 adjacent the aperture Z and the outer or rearward end e of the feed nut Y is exteriorly threaded for the reception of a nut f which bears against the rearward surface of the lug c. Preferably a lock washer g 110

of a well known type is interposed between the nut *f* and the lug *c* to prevent unscrewing of the nut *f*.

Although only an intermediate portion of the feed screw *X* is shown in the drawings, it is to be understood that said feed screw may be of a well known type which is anchored to the shell *V* against longitudinal movement with respect thereto and provided at its rearward end with suitable means, such as a crank, whereby the feed screw *X* may be rotated in order to advance the rock drill *A* in accordance with the penetration of the cutting implement (not shown) into the rock, as well as for retracting the drill after the hole has been drilled.

In practice, whenever it is desired to convert a hand held drill into one of the drifter type, the usual back head and handles may be removed from the drill body and a back head *F* substituted therefor. After such substitution of parts, the carriage *H* may be placed in position and clamped to the forward portion of the drill by means of the bolts *L* and nuts *P*. Thereafter the feed nut *Y* and the nut *f*, which may be the same feed nut and lock nut wherewith the shell *V* is equipped, may be placed in the operative positions and the feed screw *X* may then be threaded into the feed nut *Y*. After the parts have been thus assembled and secured to the rock drill and the shell, the entire assembly may be secured to suitable supporting means, such as a column or bar for use in drilling horizontal holes or holes inclined from the horizontal.

The foregoing described invention has

been found particularly advantageous for use on small work in which it is desired to drill both "down holes" and horizontal holes and in which the work does not warrant a great outlay or expenditure of money for equipment, that is, for both the hand held drill and a drifter. Inasmuch as tools of the type to which the present invention is applied are sufficiently rugged to withstand the severe usage to which they are subjected in both types of drilling this invention makes possible a considerable saving, not only in money, but in the matter of time as well.

I claim:

A mounting for a rock drill, comprising in combination with a cylinder and back head, side bolts for securing the back head to the cylinder, a lug on the back head having an aperture, a carriage, a bearing on the carriage to receive the cylinder, a clamping plate, bolts in the bearing and the clamping plate for securing the cylinder to the carriage, said bolts extending between the cylinder and the side bolts, ribs on the carriage for slidably engaging a rock drill shell, said carriage having an aperture registering with the aperture in the lug, a feed screw, a feed nut in the apertures in threaded engagement with the feed screw for moving the carriage longitudinally of the feed screw, and a nut on the feed nut for clamping the rearward end of the carriage to the lug.

In testimony whereof I have signed this specification.

EARL B. LEAR.
